HOOD FOR FIREPLACE SCREENS

Marvin L. Stark, Anchorage, and Frank C. Lewis, Louisville, Ky., assignors to Peerless Manufacturing Division, Dover Corporation, Louisville, Ky., a corporation of Kentucky

Filed June 7, 1965, Ser. No. 85,596

Term of patent 14 years

(Cl. D81—5)

FIG. 1.

FIG. 2.

FIG. 3.

FIG. 4.

FIG. 5.

FIGURE 1 is a perspective view of a hood for fireplace screens showing our new design.

FIGURE 2 is a top plan view of the hood for fireplace screens shown in FIG. 1.

FIGURE 3 is a bottom plane view of the hood for fireplace screens shown in FIG. 1.

FIGURE 4 is a rear elevational view of the hood for fireplace screens shown in FIG. 1.

FIGURE 5 is an enlarged and elevational view of the hood for fireplace screens shown in FIG. 1.

We claim:

The ornamental design for a hood for fireplace screens, substantially as shown.
